Atty's:

UNITED STATES PATENT OFFICE.

ARNOLD V. BROWN, OF OAK PARK, ILLINOIS.

TIP FOR WEBBING.

1,420,812.

Specification of Letters Patent. Patented June 27, 1922.

Application filed September 23, 1921. Serial No. 502,633.

To all whom it may concern:

Be it known that I, ARNOLD V. BROWN, a citizen of the United States, residing at Oak Park, county of Cook, State of Illinois, have 5 invented a certain new and useful Improvement in Tips for Webbing, and declare the following to be a full, clear, and exact description of the same, such as will enable others skilled in the art to which it pertains to make and use the same, reference being had to the accompanying drawings, which form a part of this specification.

My invention has for its object to produce a simple and novel expedient whereby 15 the free end of a piece of webbing may be engaged to a buckle or the like without the necessity of stitching the webbing, the engagement being a detachable one and being readily made.

20 The various features of novelty whereby my invention is characterized will herein-after be pointed out with particularity in the claims; but, for a full understanding of my invention and of its object and advantages, reference may be had to the following detailed description taken in connection with the accompanying drawing, wherein:

Figure 1 is a rear elevation of a piece of webbing such as used in hose supporters and 30 the like, connected to a buckle in accordance with my invention;

Fig. 2 is a section on an enlarged scale, taken approximately on line 2—2 of Fig. 1;

Fig. 3 is a perspective view of the metal 35 binding piece for the webbing;

Fig. 4 is a rear view of the free end of a piece of webbing having thereon a binding and attaching element somewhat different from that shown in Figs. 1, 2 and 3;

40 Fig. 5 is a section taken approximately on line 5—5 of Fig. 4;

Fig. 6 is a perspective view of the free end of a piece of webbing having thereon still another form of attaching device; and

45 Fig. 7 is a view similar to Fig. 6, showing still another modification.

Referring to the drawing, 1 represents the back plate of any usual or suitable form of buckle through which a piece of webbing, 50 2, is adapted to pass. In accordance with my invention I place on the free end of the webbing a metal element which may serve both as a binding for the raw edge and as a clip detachably to connect the said free 55 end of the webbing to the back plate of

the buckle. In the arrangement shown in Figs. 1 to 3, the attaching means consists of a plate of sheet metal folded on itself along the longitudinal center line so as to form a U-shaped trough open at the ends. One 60 of the walls, 3, of the trough is provided with teeth or prongs, 4, struck inwardly therefrom. The free end of the webbing is placed in the trough, the sides 3 and 5 of which are then closed together so as 65 to cause the teeth or prongs to penetrate the webbing and fasten the metal piece to the webbing. In clamping the metal piece upon the webbing the long free edge of the wall 5 is preferably left spaced apart 70 slightly from the adjacent face of the webbing so that when the webbing is threaded through the buckle, the lower edge of the back plate, 1, may be inserted between the wall 5 and the adjacent surface of the webbing, as shown in Fig. 2; the metal clip thus 75 serving as a broad flat hook. Then when the webbing is passed over the top of the back plate and carried down in rear thereof, the pull upon the free end of the webbing is 80 in a direction tending to draw the hook more tightly upon the back plate.

In Figs. 4 and 5, I have shown an arrangement in which an elongated clip, 6, U-shaped in cross section, is clamped firmly 85 upon the free end of the webbing, two prongs or fingers, 7, being struck up from the ends of the clip to form hooks adapted to engage with the lower edge of the back member of the buckle.

90 In the arrangement shown in Fig. 6, the attaching clip consists of a wire, 8, extending transversely across the webbing near the free end of the latter, the ends of the wire passing through the webbing and then downwardly as indicated at 9; while the extreme ends of the wires are bent upwardly to form hooks, 10, which, when the webbing is threaded through the buckle, engage with the lower edge of the back plate.

100 In Fig. 7 the clip is also made of wire, the same consisting of a cross bar, 11, having the ends bent downwardly and then upwardly to form U-shaped seats, 12, the extreme ends of the wire extending upwardly beyond the cross bar and, after passing through the webbing, being bent downwardly as indicated at 13 so as to fasten the wire firmly to the webbing. When the webbing is threaded through the buckle the 110

cross bar, 11, lies in rear of the back plate while the lower edge of the latter rests in the seats 12.

It will thus be seen that in each of the 5 forms of my invention disclosed, the necessity of sewing the free end of the webbing to the buckle or of stitching it for any other purpose, is avoided. Furthermore, a saving of webbing results from the fact that 10 the webbing need not be folded around the lower cross bar of the back plate. In each instance, the metal clip is attached to the webbing before the latter is placed in the buckle, the attachment constituting an exceeding simple operation; and the operation 15 of fastening the free end of the webbing to the buckle is likewise a simple one requiring no appreciable time for its consummation.

20 While I have illustrated and described with particularity only a few forms which

my invention may take, I do not desire to be limited to the exact structural details thus illustrated and described; but intend to cover all forms and arrangements which 25 come within the terms employed in the definitions of my invention constituting the appended claims.

I claim:

1. The combination with a bar member 30 of a buckle, of a webbing having thereon a hook engaged over an edge of said member.
2. The combination with a bar member 35 of a buckle, of a webbing having on an end thereof a clip extending across the same and provided with a portion forming a broad flat hook engaged with an edge of said bar.

In testimony whereof, I sign this specification.

ARNOLD V. BROWN.
